DISPENSING APPARATUS

Maurice H. Sacharow, Cleveland Heights, Ohio

Application January 6, 1936, Serial No. 57,669

10 Claims. (Cl. 221—104)

This invention relates to improvements in dispensing apparatus, particularly apparatus for dispensing tooth powder and the like.

One of the objects of the invention is the provision of means for laying down a predetermined amount of powder upon a tooth brush when the latter is projected into the casing of the apparatus, the dispensing of the powder being controlled automatically by the movement of the brush into the casing.

Another object is the provision of apparatus of this character wherein a bottle or like container may be employed as a replaceable part of the powder holder, and particularly where the bottle neck is shaped to assist in the even distribution of the powder lengthwise of the brush.

Still another object is the provision of means for collecting and disposing of surplus powder.

A further object is the provision of means for starting the dispensing of powder at a point spaced from the extremity of the brush, where it would be especially subject to spillage.

Other objects and features of novelty will appear as I proceed with the description of those embodiments of the invention which, for the purposes of the present application, are illustrated in the accompanying drawing, in which

Fig. 1 is a vertical longitudinal view of an apparatus embodying the invention, including a fragmentary showing of a bottle in position in the hopper.

Fig. 2 is a transverse vertical section taken substantially on the line 2—2 of Fig. 1.

Fig. 3 is a further transverse section taken on the line 3—3 of Fig. 1.

Fig. 4 is a view similar to Fig. 1, showing a modified construction in which is mounted a bottle of ordinary form.

Fig. 5 is a horizontal sectional view taken substantially on the line 5—5 of Fig. 4.

Fig. 6 is a detail sectional view taken substantially on the line 6—6 of Fig. 4.

Fig. 7 is a fragmental view, partly in vertical section, showing a bottle with a rectangular neck mounted in a hopper like that of Figs. 4 and 5, and

Fig. 8 is a cross section taken substantially on the line 8—8 of Fig. 7.

The apparatus with which the present invention is concerned is intended for one-hand operation, that is to say by the mere insertion of a tooth brush a predetermined quantity of tooth powder is caused to be deposited evenly along a predetermined length of the brush. It is necessary to provide spring means to resist the move-

ment of the tooth brush and return the parts to normal position after operation, and hence it is essential either to make the apparatus heavy so that it will not be readily dislodged when resting on a table or other support, or to attach it to a fixed support. I prefer the latter alternative and have so illustrated the invention.

I have shown a body member or casing comprising two side walls 10, each of which has an inwardly directed flange at the top of the casing. 10 The forward portions of these flanges are straight, as indicated at 11 in Fig. 3. To the rear of these straight flange portions there are other flange portions 12, shown in section in Fig. 2. These curved flange portions 12 form a seat 15 for a shelf 13, preferably semi-cylindrical, formed at the bottom of a sheet metal hopper 14.

At their rear ends the walls 10 of the body member are provided with tabs 15 which are projected through slots formed in a back member 20 16, the tabs being folded down against the rear surface of the back to make a tight joint. I provide a pair of separated base members 17 preferably formed integral with the back 16. For this purpose the sheet of metal from which the back is formed is given a right angle bend, after which a rectangular central section is cut from the remainder leaving the members 17 which are directed outwardly or forwardly from the back at a right angle. Slots 19 may be punched in 30 the base members 17 if desired, in order to utilize those members as a tooth brush holder.

The inner edges of the base members 17 are folded upwardly around the walls 10 of the body, as indicated in Figs. 2, 3, and 6, and these flanges 35 are utilized further as tracks as for a drawer 42 having outturned flanges 43 cooperating with the aforesaid tracks. Lengthwise of the drawer I mount a plurality of wires 44 separated sufficiently to permit free flow of powder into the 40 drawer while supporting a brush inserted into the apparatus.

The forward end of the body may be reenforced and given a finished appearance by the application of a frame 20 which is angular in cross 45 section so as to embrace the body and also to cover the sharp edge of the metal of which the body members are constructed.

On the rear surface of back member 16 I secure by welding or otherwise, or by striking out 50 from the back itself, a horizontal loop member 22 which is adapted to be slipped over a hook of suitable character fastened to a supporting wall.

The shelf 13 of the hopper is soldered or otherwise secured to the curved flanges 12 of the body 55

member. In the form of the invention illustrated in Fig. 1 there is a rounded shoulder 23 against which the rim of a bottle 24 rests when placed in position in the apparatus. The neck of the bottle preferably fits the upper cylindrical end of the hopper snugly, so that when the bottle is in position it is yieldably held there against accidental displacement. Of course in practice, when it is desired to put a new bottle of powder into the apparatus, the casing is removed from the wall, inverted, and slipped over the neck of the bottle from which the cork has been previously removed. When the two parts are thus secured together, the assembly of the casing and bottle is turned over and mounted on the wall.

The hopper 14 has an opening 25 at one end just above the curved shelf 13. It is through this opening that powder is discharged. The opening is normally closed by an approximately semi-circular plate 26 which is carried by a flat bar 27. At the opposite end of the shelf 13 when the parts are in normal position there is a scraper 28, also carried by bar 27, and of the same shape and size as plate 26. Between the plate 26 and scraper 28 the bar 27 is provided with a relatively-wide slot 29, through which powder may descend and cover the shelf 13. Just above the scraper 28 there is a pin 30 which has a powder stirring or agitating function when the bar 27 is moved longitudinally. The forward end of the bar 27 is turned downwardly and formed into a semi-cylindrical plate 31, similar to the parts 26 and 28, this plate being slotted on each side to receive the flanges 11. By this means the forward end of bar 27 is guided.

On the rear end of bar 27 there is a depending arm 32 which projects downwardly through the space between the curved flanges 12 of the body member, but is somewhat wider than that space and is slotted to receive those flanges slidably, whereby the rear end of the bar is guided. The arm 32 is urged forward by a flat spring 33 which is secured to the back 16, preferably by being projected through a slot in the back and bent up against the back, to which it may be soldered. The forward end of the spring bears loosely against the arm 32.

When a tooth brush is projected through the opening in the forward end of the body member 10 and caused to engage arm 32, further movement of the brush in the same direction slides the bar 27 rearwardly against the action of spring 33. As soon as the closure plate 26 passes through opening 25 powder in the hopper begins to move through opening 25 and onto the brush. The scraper 28 imparts a positive movement to the powder, which is deposited progressively on the brush in even amount as the brush moves rearwardly. At the same time I prevent powder from falling down onto the shelf to the rear of the traveling scraper 28, this being effected by the portion of the bar 27 to the rear of the scraper, which portion acts as a tongue bridging the space across the semi-cylindrical shelf. The bar 27 being efficiently guided at both its rear and forward ends cannot tilt due to the action of spring 33 or otherwise. As soon as the brush has been pushed into the casing as far as it will go, and the delivery of powder has been completed, the brush is withdrawn and the spring 33 returns the parts to their normal position, a new supply of powder falling onto the shelf 13, and the plate 26 advancing to close the opening 25.

In order to keep the tooth brush centrally arranged as it is moved into the casing I may

supply spring guides 34 which are secured to the inner walls of body member 10 at 35.

In the apparatus above described it is contemplated that a bottle 24 with an ordinary round neck will be employed. I prefer however to use a special bottle with a transversely elongated rectangular neck, as illustrated at 36 in Figs. 7 and 8. The hopper may be constructed to receive such a bottle only, or it may be formed as illustrated at 37 in Figs. 4, 5, 7 and 8, so as to receive a round necked or a rectangular necked bottle interchangeably. In this case the said elements of the hopper have end portions 38 that are straight and intermediate portions 39 that are curved. Grooves 40 extend throughout both of these side portions and are adapted to releasably grip the rim of either type of bottle, due to the resilience of the metal of which the hopper is made. Because of the fact that the slot 29 is necessarily long and narrow, to correspond with the shape of the brush, the rectangular necked bottle cooperates with the slot in its delivery of powder to better advantage than a round necked bottle. In Fig. 4 however a round necked bottle 41 is shown with its rim gripped by the curved portions of the grooves.

When the apparatus is properly operated there is very little spillage of powder, but in order to catch whatever powder may fall off the brush while it is in the casing I prefer to employ the small sheet metal drawer 42 previously described. The wires 44 of this drawer form a support for the brush when the latter is inserted into the casing. Whenever any considerable amount of powder collects in the drawer, the latter is pulled out and emptied, and then replaced.

The operation of the apparatus will be obvious from the foregoing description of its construction. One point which is to be noted however is that I space the depending arm 32 somewhat beyond the hopper, that is in the normal position of the parts. This is for the purpose of preventing the deposit of powder upon the very tip of the brush, because that is the part of the brush from which the powder spills most readily. The length of the shelf 13 should also be such that the delivery of powder will stop before the rear end of the bristle portion of the brush comes beneath the opening 25. The forward end of the shelf 13 may be closed except for a slot to accommodate the bar 27. However, it is satisfactory to leave this end of the shelf open also, as illustrated in Fig. 1, as the scraper 28 may be relied upon to prevent powder from sifting down when the parts are in normal position.

Having thus described my invention, I claim:

1. In a dispenser of the character described, a container arranged with its discharge end down, a shelf at the bottom of the container onto which material may be deposited from the container, said container having an opening therethrough directly above one end of said shelf, a scraper movable along said shelf toward said opening, and a depending arm operatively connected with said scraper through said opening, whereby movement of the arm may be effected in a forward direction by means of a brush projected into the dispenser, thereby causing the scraper to push material out of said opening onto the brush.

2. In a dispenser of the character described, a container arranged with its discharge end down, a shelf at the bottom of the container onto which material may be deposited from the container, said container having an opening therethrough directly above one end of said shelf, a scraper

- movable along said shelf toward said opening, and a depending arm operatively connected with said scraper through said opening, said arm being spaced a substantial distance from said opening in the normal position of the parts, whereby movement of the arm may be effected in a forward direction by means of a brush projected into the dispenser, thereby causing the scraper to push material out of said opening onto the brush. 5
- 10 3. In a dispenser of the character described, a container arranged with its discharge end down, a shelf at the bottom of the container onto which material may be deposited from the container, said container having an opening therethrough directly above one end of said shelf, a scraper movable along said shelf toward said opening, and a depending arm operatively connected with said scraper through said opening, whereby movement of the arm may be effected in a forward direction by means of a brush projected into the dispenser, thereby causing the scraper to push material out of said opening onto the brush, said operative connection carrying a closure adapted to substantially fill said opening in the normal position of the parts. 15
- 15 4. In a dispenser of the character described, a container arranged with its discharge end down, a shelf at the bottom of the container onto which material may be deposited from the container, said container having an opening therethrough directly above one end of said shelf, a scraper movable along said shelf toward said opening, and a depending arm operatively connected with said scraper through said opening, whereby movement of the arm may be effected in a forward direction by means of a brush projected into the dispenser, thereby causing the scraper to push material out of said opening onto the brush, and a tongue attached to said scraper and adapted to cover said shelf to the rear of the scraper as the latter moves toward said opening, whereby the amount of material passed through the opening 20 is definitely limited. 25
- 20 5. In a dispenser for tooth powder and the like, an elongated casing having an opening in one end through which a tooth brush may be projected, means for depositing powder onto said brush while it is within the casing, and a drawer in the bottom of said casing adapted to receive surplus powder, said drawer comprising a foraminous top. 30 35
- 25 6. In a dispenser of the character described, a container arranged with its discharge end down, a shelf at the bottom of the container onto which material may be deposited from the container, said container having an opening therethrough directly above one end of said shelf, a scraper movable along said shelf toward said opening, a depending arm operatively connected with said scraper through said opening, whereby movement of the arm may be effected in a forward direction by means of a brush projected into the dispenser, thereby causing the scraper to push material out of said opening onto the brush. 40 45
- 30 7. In a dispenser of the character described, a container arranged with its discharge end down, a shelf at the bottom of the container onto which material may be deposited from the container, said container having an opening therethrough in line with said shelf, the dispenser having a brush receiving compartment below said opening, a scraper movable along said shelf toward said opening, and an arm operatively connected with said scraper in position for engagement by the forward end of the brush, whereby movement of the brush forwardly beneath the shelf causes the scraper to push material out of said opening. 50 55
- 35 8. In a dispenser of the character described, a casing having an upwardly extending resilient sheet metal hopper, means in the casing for depositing material from the hopper onto a brush when the latter is projected into the casing, the wall of the hopper having therein a horizontal groove for receiving and resiliently retaining the bead on a beaded neck container. 60
